UNITED STATES PATENT OFFICE

BRONALD FRANCIS NAGLE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

CENTRIFUGAL RELAY

Application filed April 22, 1929. Serial No. 357,214.

My invention relates to electrical relays of the centrifugal type, and has for an object the provision of novel and improved means for selectively operating one contact or another according as the centrifugal device revolves in one direction or the other.

I will describe one form of relay embodying my invention, and will then point out the novel features thereof in claims.

10 In the accompanying drawings, Fig. 1 is a view, partly in side elevation and partly diagrammatic, showing one form of relay embodying my invention. Fig. 2 is a top plan view, partly sectioned, of part of the relay shown in Fig. 1. Fig. 3 is a fragmentary view illustrating the operation of a portion of the relay shown in Fig. 1.

Similar reference characters refer to similar parts in each of the views.

20 Referring first to Fig. 1, the relay comprises an alternating current electric motor M having a rotor 5 and two stator windings 3 and 4. One of the stator windings 3 is constantly energized from the secondary 2 of a transformer T, the primary 1 of which is supplied with alternating current from a source not shown in the drawings. The other stator winding 4 is connected with the transformer secondary 2 through a pole-changer P, whereby this winding is supplied with alternating current of one relative polarity or the other according as pole-changer P is in one position or the other. It follows that the rotor 5 will revolve in one direction or the other according as pole-changer P is in one position or the other.

25 The relay further comprises a centrifugal device C which is operated by the motor M. This device involves a spindle 6 which is mounted to rotate on a vertical axis and is constantly connected with the rotor 5 of motor M. The spindle 6 is provided with a plurality of yokes such as 7 and 7^a in which the centrifuge arms such as 8 and 8^a are pivotally mounted. These arms are provided with the usual weights 10 and 10^a, and with the usual rollers 9 and 9^a which coact with a groove 11^a in a block 11. Journalled in the block 11 by means of a ball bearing 12 is a member 13, which member is therefore con-

strained to move longitudinally with the block 11, but may revolve with relation to the block. The member 13 is provided with a stem 14 which projects vertically upwardly, and the upper end of which is provided with an arm 23 which projects at right angles to the axis of rotation of the member 13. Projecting in opposite directions from the arm 23 are two arcuate pins 15 and 15^a, as shown more clearly in Fig. 2.

55 Two contact operating arms 16 and 16^a are pivotally mounted at 18 and 18^a, respectively, in fixed supports 19 and 19^a, respectively. Arm 16 is biased by a counterweight 20 to swing in counterclockwise direction, and arm 16^a is biased by a counterweight 20^a to swing in clockwise direction. The inner or adjacent ends of these arms are provided with vertically disposed slots 17 and 17^a, respectively, so located as to be in the paths of the pins 15 and 15^a, respectively, when the centrifuge member 13 is in its lowest position. Each contact operating arm carries a contact spring 21 arranged to coact with a fixed contact member 21^a, and a second contact spring 22 arranged to coact with a fixed contact member 22^a. It follows that when the contact operating arms are unaffected by the centrifugal device, each contact 22—22^a is closed and each contact 21—21^a is open.

60 The operation of the relay is as follows: When the motor M is at rest, the centrifuge block 11 and the associated member 13 will be in their highest positions. The pins 15 and 15^a may be in the positions in which they are shown in Fig. 2, or one of these pins or the other may project into its associated slot 17 or 17^a, but the positions of these pins are immaterial, because in any event the contact operating arms 16 and 16^a will be in their normal positions in which they are shown in the drawings. I will now assume that the motor M starts to rotate in such direction that the centrifuge block 11 rotates in clockwise direction as viewed in Fig. 2. This block will carry with it the member 13 until the pin 15^a enters the slot 17^a and the arm 23 engages the side of the arm 16^a. Further rotation of the member 13 will then be prevented, and as 65 the speed of the centrifugal device increases,

the member 13 will be moved downwardly, so that the pin 15* will swing the arm 16* in counter-clockwise direction, as viewed in Fig. 1, with the result that the associated contact 22—22* will be opened and the associated contact 21—21* will be closed. The pin 15 is then, of course, entirely disassociated from arm 16 so that this arm and the contacts operated thereby remain in their normal positions.

If now the motor M comes to rest and starts to revolve in the opposite direction, pin 15 will enter slot 17 in arm 16, with the result that this arm will be swung in clockwise direction against the biasing force exerted by counterweight 20, so that the contacts operated by arm 16 will be reversed. During such operation the arm 16* and contacts associated therewith will remain in their normal positions.

Relays embodying my invention are particularly well adapted for use as track relays in railway signaling systems applied to railroads having alternating propulsion current. In such cases, the propulsion current is usually of a lower frequency than the track circuit or signaling current, so that if the motor M is improperly energized by propulsion current, it will revolve at a lower speed than when it is energized by signaling current. One reason for making the apertures 17 and 17* in the form of slots is to prevent operation of the relay contacts in the event that the motor M is thus energized by current of the propulsion frequency. Referring to Fig. 3, in the event of energization of motor M by propulsion current, the pin 15 will move downwardly to the lower end of slot 17 but will move no further because the speed of the motor M will not be such as to create sufficient torque on arm 16 or 16* to lift the counterweight 20 or 20*. This operation of the motor will therefore have no effect on the contacts.

When the motor is operated by current of the signaling frequency, however, the centrifuge members 11 and 13 will be moved farther down, with the result that the pin 15 will engage the lower end of the slot 17 and will move the arm 16 to the position shown in dotted lines in Fig. 3, this movement being sufficient to reverse the contacts operated by the arm 16.

The centrifugal device C may be so designed and proportioned that when it is at rest the effect of the weights 10 and 10* is sufficient to hold the block 11 in its highest position. If this is undesirable, however, the same effect may be secured by suspending the block 11 and the member 13 by means of a wire 24 and a spring 25, thereby relieving the weights 10 and 10* of the necessity for restoring the rotating parts of the device to their initial positions. The wire 24 is attached to the upper end of the stem 14, and

inasmuch as this stem rotates through only a portion of a complete turn, it follows that the torque exerted by the wire 24 and the spring 25 is negligible in so far as the operation of the relay is concerned.

Although I have herein shown and described only one form of relay embodying my invention, it is understood that various changes and modifications may be made therein within the scope of the appended claims without departing from the spirit and scope of my invention.

Having thus described my invention, what I claim is:

1. A relay comprising a centrifugal device rotatable in opposite directions, two contacts, a member biased to one longitudinal position and movable away from said position by the centrifugal action of said device, said member being free to rotate with respect to said device but coupled thereto by a slip connection, two operating arms one for each of said contacts and each having a slot, and two pins carried by said member one of which enters the slot in one arm or the other of which enters the slot in the other arm according as said member turns in one direction or the other.

2. A relay comprising a centrifugal device rotatable in opposite directions, two contact operating arms each biased to one position and each disconnected from said device when the device is at rest, means determined by the direction of rotation of said device for connecting the device with one or the other of said arms to move such arm away from its biased position by the centrifugal action of said device, and contacts operated by said arms.

3. A relay comprising a centrifugal device rotatable in either direction, and including a rotatable block moved longitudinally by the centrifugal action of said device, a member journaled in said block to move longitudinally therewith, said member being free to rotate with respect to said block but coupled thereto by a slip connection, two pins fixed to said member and projecting in opposite directions, two contact operating arms each biased to one position and each provided with a hole to receive one of said pins according as said member tends to rotate in one direction or the other when the device starts from rest, whereby one arm or the other is moved away from its biased position due to longitudinal movement of said member, and contacts operated by said arms.

4. A relay comprising a centrifugal device rotatable in either direction, and including a member which is coupled with the device by a slip connection and is moved longitudinally away from a biased position by the centrifugal action of said device, two contact arms each biased to one position and movable away from such position by the longitudinal motion

of said member when it is connected with the member, means determined by the direction in which said member tends to rotate when the device starts from rest for operatively connecting the member with one or the other of said arms, and contacts operated by said arms.

5. A relay comprising a centrifugal device rotatable in either direction and including a member which is coupled with the device by a slip connection and is moved longitudinally away from a biased position by the centrifugal action of said device, two pins projecting in opposite directions from said member and disposed in planes perpendicular to the axis about which the member tends to rotate, two contact arms each biased to one position and each provided with a hole adapted to receive one of said pins when said centrifugal device starts from rest whereby one or the other of said arms will be moved away from its biased position due to longitudinal movement of said member according as said device is rotated in one direction or the other, 20 and contacts operated by said arms.

In testimony whereof I affix my signature.
RONALD FRANCIS NAGLE.
